Primary Examiner — Brett Miller(74) *Attorney, Agent, or Firm* — Steven H. Washam;
Washam PLLC(57) **CLAIM**

We claim the ornamental design for a shark shape silicone mold, as shown and described.

DESCRIPTION

FIG. 1 is a perspective view of a shark shape silicone mold showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof, featuring section lines 8 and 9 representing subsequent views FIG. 8 and FIG. 9, respectively;

FIG. 7 is a bottom plan view thereof;

FIG. 8 is a sectional rear elevational view thereof; and,

FIG. 9 is a sectional right-side elevational view thereof.

The broken lines in the drawings are for illustrating environmental structure only and form no part of the claimed design.
